UNITED STATES PATENT OFFICE.

CLAUDE A. BARNES, OF ROLLING PRAIRIE, INDIANA, ASSIGNOR OF ONE-HALF TO
JAMES A. BIRCHIM, OF ROLLING PRAIRIE, INDIANA.

FREIGHT-CAR DOOR.

1,032,266.

Specification of Letters Patent.

Patented July 9, 1912.

Application filed July 27, 1911. Serial No. 640,812.

To all whom it may concern:

Be it known that I, CLAUDE A. BARNES, a citizen of the United States, residing at Rolling Prairie, in the county of Laporte 5 and State of Indiana, have invented a new and useful Freight-Car Door, of which the following is a specification.

The invention relates to improvements in freight car doors.

10 The object of the present invention is to improve the construction of freight car doors, and to provide a simple, efficient and comparatively inexpensive car door, designed for use on the exterior of box cars, 15 stock cars and the like, and capable of affording a storm-proof closure of great strength and durability.

10 A further object of the invention is to provide a pivotally mounted car door of this character, adapted when unlocked to swing toward its open or closed position through gravity, whereby the door may be easily operated and readily moved to either its open or closed position with little effort.

25 With these and other objects in view, the invention consists in the construction and novel combination of parts hereinafter fully described, illustrated in the accompanying drawing, and pointed out in the claims 30 hereto appended; it being understood that various changes in the form, proportion, size and minor details of construction, within the scope of the claims, may be resorted to without departing from the spirit or sacrificing any of the advantages of the invention.

35 In the drawing:—Figure 1 is an elevation of a portion of a freight car provided with a door, constructed in accordance with this 40 invention and shown closed. Fig. 2 is a longitudinal sectional view of the same, the door being open. Fig. 3 is a detail sectional view on the line 3—3 of Fig. 1. Fig. 4 is a detail sectional view on the line 4—4 45 of Fig. 1.

Like numerals of reference designate corresponding parts in all the figures of the drawing.

50 In the accompanying drawing in which is illustrated the preferred form of the invention, 1 designates a freight car door pivoted at its upper rear corner by a horizontal bolt 2, or other suitable fastening device, and ar-

ranged to swing backward and forward to uncover the door opening 3 of a car 4 and 55 to cover or close the same. The pivoted door, which is arranged on the exterior of the car 4, is adapted to swing by gravity nearly to its open or closed position, and it requires but little effort to complete the 60 opening or closing movement of the door, which is locked in its closed and open positions by front and rear catches 5 and 6 to prevent it from swaying or oscillating or projecting below the bottom of the body of 65 the car when it is unfastened. The door 1 is provided at its upper rear corner with a hinge element 7, constructed of suitable metal and having an eye or opening to receive the pivot bolt 2, and provided with 70 integral metallic straps or braces 8, diverging downwardly and forwardly from the upper rear corner of the door when the latter is closed, and secured at intervals to the door and adapted to brace and reinforce the 75 same to prevent the door from sagging. The door is also reinforced at its upper pivoted corner by a metallic binding strip 9, suitably secured to the door and arranged in flush relation with the adjacent edges of 80 the same. The bolt is supported at its outer end by a hanger or bracket 10, constructed of suitable metal and consisting of an intermediate depending portion and terminal attaching portions 11. The intermediate de- 85 pending portion is preferably in the form of a loop, and is provided at the bottom with a central opening 12 through which the pivot bolt passes. The attaching portions 11 are secured by suitable fastening 90 devices to an over-head guard 13, which receives the upper edge of the door 1.

95 The guard consists of a bar or member 14, extending longitudinally of the car above the plane of the door opening and project- ing downward and provided at its lower edge or face with a strip, extending below the bar or member 14 and forming a de- pending flange at the outer face of the door, as clearly illustrated in Fig. 3 of the draw- 100 ing. The over-head guard is of sufficient length to receive the door when the latter is in its open position. The car is provided around the door opening with a rectangular frame 15 to present a flat surface to the 105 door, and it has a curved guide or brace 16,

extending upwardly and rearwardly from the lower portion of the frame 15 and adapted to receive the door when the latter through its oscillation is carried beyond the frame 15. The curved brace or guide 16 is 5 adapted to prevent the door from moving inward laterally and straining the pivot when the door is in its open position.

The door is equipped at the corner diagonally opposite its pivot with an L-shaped 10 corner iron 17, forming a binding for the corner of the door and composed of angularly related portions and provided at the angle with an exterior enlargement 18, 15 rounded to present an outer curved face and having terminal engaging faces or shoulders 19 and 20, adapted to engage with the catches 5 and 6, whereby the door is locked in its closed and open positions. The 20 catches 5 and 6, which are constructed of suitable spring material, are secured to front and rear vertical bars 21 and 22 and consist of vertical portions and lower engaging portions 23, arranged at an angle to the vertical portions and sigmoidally curved, 25 as shown, to provide an inner concave portion to fit the rounded enlargement of the corner iron 17, and to present an outer convex or beveled face to the corner iron to permit the door in closing to engage either 30 catch automatically. The engaging portion 23 is provided at an intermediate point with a shoulder 24, preferably formed by enlarging the terminal of the catch. When the 35 door is opened or closed, the rounded portion of the corner iron 17 of the door is carried into contact with the free terminal portion of one of the catches, which catch is moved backwardly or outwardly away 40 from the door until the rounded portion 18 passes the shoulder of the catch, when the latter automatically springs into engagement with the corner iron and locks the door against movement. The catch 5 and 45 the front portion of the corner iron 17 are provided with perforated lugs 25 and 26, registering when the door is in its closed position and adapted to receive the wire of a car seal, or a lock, or other fastening means. 50 The vertical bars 21 and 22 are cut away at the inner edges of their lower portions to provide spaces or recesses 27 in which the resilient catches are adapted to operate.

The car is equipped at the front portion 55 of the door opening with upper and lower horizontally disposed guard arms or keepers 28 and 29, and it has a lower guard arm 30 at the rear vertical bar 22. The guard arms, which are bolted or otherwise secured to the 60 vertical bars 21 and 22, project from the inner edges thereof and have outwardly curved terminals 31. The terminals extend laterally beyond the plane of the door and are arranged out of the path of the same to 65 prevent the door from striking the ends of

the guard arms, which are adapted to hold the door against outward lateral movement, so that there is no liability of the door through vibration becoming accidentally disengaged from either of the catches. 70

In order to draw the rear portion of the door inwardly into tight engagement with the car when the door is closed, the car is equipped with an angularly disposed tongue 32, located at the bottom portion of the 75 frame 15 and coöoperating with a loop 33, which projects from the inner face of the door. The tongue 32 is arranged in the path of the loop and extends through the same when the door is in its closed position, 80 and as the tongue is set at an angle to the face of the car, it is adapted to draw the door inward tightly against the car, so that the door when closed will be perfectly storm-proof. The door is provided at its 85 lower front portion with a handle 34 for convenience of operating it.

Having thus fully described my invention, what I claim as new and desire to secure by Letters Patent, is:— 90

1. The combination with a freight car door pivoted at one of its upper corners, of a corner iron secured to and forming a binding for the diametrically opposite corner of the car door and having engaging faces at 95 the adjacent edges of the said door, and front and rear spaced catches located in the path of the keeper and arranged to engage the said faces thereof to hold the door in its open and closed positions, the front 100 catch and the corner iron being provided with projecting lugs having registering perforations to receive a car seal.

2. The combination with a freight car door pivoted at one of its upper corners, of a substantially L-shaped corner iron secured to and forming a binding for the diametrically opposite corner of the car door and provided at such corner thereof with an enlargement having a rounded outer face and terminal shoulders, and spaced resilient catches secured to the car and having vertical portions and lower curved portions and arranged in the path of the corner iron, said lower curved portions conforming to the 110 configuration of the enlargement thereof and fitting around the bottom edge of the corner of the door and provided with shoulders to engage the shoulders of the said corner iron to hold the door in its open and 115 closed positions.

3. The combination with a freight car having a door opening, and a car door pivoted at its upper rear corner to the car and arranged to swing backward and forward to cover and uncover the door opening, of upper and lower keepers mounted on the car at the front of the door opening and arranged to engage the outer face of the car door when the latter is closed, a loop mount 125 130

ed on the inner face of the car door at the lower rear corner thereof, a fixed angularly disposed tongue mounted on the car at the bottom of the door opening and arranged in 5 the path of and adapted to project through the loop of the car door in the closing movement thereof to draw the door inward into tight engagement with the car and to hold the lower rear corner of the door against 10 outward movement, and means located at

the front of the door for securing the same in its closed position.

In testimony, that I claim the foregoing as my own, I have hereto affixed my signature in the presence of two witnesses.

CLAUDE A. BARNES.
